UNITED STATES PATENT OFFICE.

LEMUEL LESTER STEVENSON, OF EMPORIA, KANSAS.

PHOTOPRINT-ADJUSTER.

1,275,784.

Specification of Letters Patent. Patented Aug. 13, 1918.

Application filed March 2, 1917. Serial No. 152,040.

To all whom it may concern:

Be it known that I, LEMUEL LESTER STEVENSON, a citizen of the United States, and a resident of Emporia, in the county of Lyon and State of Kansas, have invented a new and Improved Photoprint-Adjuster, of which the following is a full, clear, and exact description.

My invention relates to the printing of photographs, and the main object thereof is to provide means for instantly, automatically and accurately adjusting the print paper upon the negative, the adjusting means being of relatively great thickness when free from pressure though of actually slight thickness when under pressure due to their peculiar and novel formation.

My invention is fully described in the following specification, of which the accompanying drawings form a part, in which like characters refer to like parts in each of the views, and in which:

Figure 1 is a view of a mask provided with my invention, arranged within a printing frame having its pressure-back removed.

Fig. 2 is a section taken on the line 2—2 of Fig. 1;

Fig. 3 is a face view of one of my adjusting devices, in one embodiment thereof; 30 and

Fig. 4 is an edge view thereof looking away from the print paper.

Referring to Figs. 1 and 2, 5 represents an ordinary printing frame wherein the negative 6 is placed and, when the print paper 7 is arranged in place, the pressure-back of the frame is applied and the print paper is held immovable on the negative during the exposure, a mask 8 being illustrated for limiting the area of the negative to be printed, and said mask is provided with a number of my adjusters 9.

Each adjuster consists of a tongue of fairly stiff material flexed from end to end 45 so as to cause the inner edges 10 thereof to gradually rise above the surface upon which the adjusters rest, as shown in Fig. 4, whereby a gradually thickened shoulder is presented to the relatively thin print paper, 50 although the adjusters may be formed of material just as thin as the print paper, or even thinner, these inner edges 10 being arranged along the lines to be occupied by the respective edges of the print paper.

55 A twist to the tongues is imparted to the adjusters when being manufactured by

reason of their flexing along a line inclined with respect to their transverse axes, as seen particularly in Figs. 1 and 4, so that in their movement away from the plane of the mask, 60 their inner edges 10 will recede from the lines to be occupied by the print paper. This shape is permanent although yielding to pressure, with the result that a plurality of relatively thick print paper guides are provided at the desired points but which guides flatten under the pressure of the back-plate of the printing frame and, in their movement to flat form, the edges 10 of the tongues will shift slightly in an inward lateral direction and thus tend to shift the print paper into desired position if not already in such position.

The form shown in Figs. 3 and 4 is for use where the integral structure of mask and 75 tongues shown in Figs. 1 and 2 is not desired, as the tongues 11 may have their bases 12 secured to the negative itself, to a mat, or to the glass in a printing frame or machine, as by an adhesive, solder, rivets or 80 any other suitable means, and operate as efficiently as those shown in Figs. 1 and 2.

The adjusters may be cut from the mask as shown, or they may be mounted thereon, and I will also vend the devices in the simple form shown in Figs. 3 and 4, ready for attachment to any surface, this latter form presenting a quick, positive and inexpensive device for the purpose specified.

While I have shown the adjusters of a 90 preferred configuration, I do not desire to limit myself thereto, nor to any special conformation, nor to any special material, and I reserve the right to make other changes thereover provided such changes come within the spirit of the invention and within the scope of the appended claims.

Having fully described my invention, what I claim as new, and desire to secure by Letters Patent, is:

1. A photo print adjuster, comprising a mask having a plurality of photo print adjusting members, each consisting of a flat resilient strip secured at one end to the mask and flexed on a line transversely inclined to its contact edge toward the free end of the tongue to normally present an edge at its opposite free end gradually inclined with respect to the face of the mask, said inclined free end being yieldable flatwise 110 against the mask under pressure.

2. In a photo print adjuster, the combina-

tion with a support, of a tongue of resilient sheet material flexed on a line transversely inclined to its contact edge toward the free end of the tongue to present an edge to a
5 print gradually inclined with respect to the face of said sheet, said tongue yielding under pressure flush with the face of said sheet.

3. A photo print adjuster, consisting of a
10 sheet of material having tongues, said tongues being flexed on lines transversely inclined to their contact edges toward the free ends of the tongues to present edges to a sheet gradually inclined with respect to the face of said sheet and yielding into flat
15 form under pressure.

4. A photo print adjuster, consisting of a
20 mask of sheet material having an opening and having tongues adjacent to said opening, said tongues being flexed on lines transversely inclined to their contact edges toward the free ends of the tongues, to present edges to a mask gradually inclined with respect to the face of said mask and yielding
25 into flat form under pressure.

5. A photo print adjuster comprising a
25 mask having a plurality of photo print adjusting members, each including a normally
30 upstanding tongue of flat resilient material secured at one end to the mask and intermediately flexed on a line transversely in-

clined to its contact edge toward the free end of the tongue, whereby to shift slightly in a lateral direction when flattened under pressure.

35

6. A photo print adjuster comprising a mask having an opening and a series of resilient tongues adjacent said opening, each of said tongues having a portion thereof secured to said mask and being flexed transversely so that the other part lies normally inclined to the face of the mask and with one edge inclined with respect to the adjacent edge of the opening, and is yieldable so that it lies parallel to said edge of said
40 opening when the tongue is pressed flatwise against the mask.

45

7. A photo print adjuster tongue, comprising a plate provided at one end with means for securing it to a support, and bent
50 intermediate of its ends on a line transversely inclined to its contact edge toward the end of the tongue opposite that having the securing means.

55

8. A photo print adjuster tongue, comprising a plate provided at one end with an adhesive substance for securing it to a support and bent intermediate of its ends on a line transversely inclined to its contact edge toward the end of the tongue opposite that
60 having the adhesive substance.

LEMUEL LESTER STEVENSON.
